UNITED STATES PATENT OFFICE.

WALTER EDWARD BEREITER, OF ZION CITY, ILLINOIS.

HOISTING DEVICE FOR ENSILAGE-BLOWERS.

1,215,241.

Specification of Letters Patent.

Patented Feb. 6, 1917.

Application filed November 14, 1916. Serial No. 131,322.

To all whom it may concern:

Be it known that I, WALTER E. BEREITER, a citizen of the United States, residing at Zion City, in the county of Lake and State of Illinois, have invented new and useful Improvements in Hoisting Devices for Ensilage-Blowers, of which the following is a specification.

This invention relates to hoisting apparatus, and it has particular reference to an improved device for hoisting the blower pipe of an ensilage chopper into proper position to be supported with respect to a silo in such a manner as to deliver the ensilage therein.

The invention has for its object to produce an improved crane including a frame, means for supporting the same in position on a silo, a step to support the operator, hoisting means for elevating the tube, and means for securing the tube in position.

A further object of the invention is to produce a device of the character described which will be simple in construction, inexpensive and efficient in operation.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings,—

Figure 1 is a perspective view showing the improved crane applied to a silo and with the blower pipe in process of being hoisted into position.

Fig. 2 is a perspective view showing the blower pipe hoisted and adjusted for operation.

Fig. 3 is a side view of the crane detached.

Fig. 4 is a front view of the same.

Corresponding parts in the several figures are denoted by like characters of reference.

The frame of the improved crane is composed of side members each consisting of a metallic bar 15 having a quarter-twisted portion 16 intermediate the ends thereof, the lower end being bent at right angles to the

body of the bar to produce a forwardly extending arm 17 having at its forward end an upturned hook 18. Each side member 15 is bent at the upper end thereof to produce a laterally extending loop or keeper 19. The arms 17 of the two side members support a step or platform 20 which may be bolted or otherwise secured on said arms, as shown at 21. The forward edge of the step or platform is also inserted beneath the hooks 18 which assist in securing the said step or platform in position. The hooks 18 are connected with the side members 15 by means of inclined braces 22 which have been shown as being provided with quarter-twisted portions 23 intermediate the ends thereof. The quarter-twisted portions of the frame bars and the braces are provided in order that the body portions of the side members and braces, as well as the arms 17, may be disposed in the proper planes.

The step or platform 20 serves in a measure to connect and to space apart the lower ends of the side members 15. Said side members are also connected together and spaced apart by means of upwardly and forwardly extending inclined convergent arms 24, each of said arms having one end secured to one of the side members 15 intermediate the ends thereof. The other ends of the arms 24 are bolted or otherwise connected together, and said arms serve to support a pulley 25 over which a flexible hoisting element, such as a chain 26, is guided. The arms 24 are reinforced by means of brace arms 27, each having one end secured to one of the side members 15 near the upper end thereof, and each being bolted upon or otherwise connected with one of the arms 24 at 28. The arms 27 are provided with terminal hooks 29, said arms being slightly spaced apart at their forward ends. A chain 30 is connected with one of the arms, at 31.

Slidably supported in the keepers 19 at the upper ends of the frame bars 15 are shanks 32, each having at its rearward end a downwardly extending hook 33 which, by proper adjustment of the shank, may be variously spaced from the rearward edge of the frame bar with which it is connected. Each shank 32 has a plurality of apertures 34, for the passage of a fastening member, such as a bolt 35, whereby it may be adjustably mounted in its keeper. The shanks 32 carrying the hook members 33 are in-

tended to be supported on the top edge 36 of the silo, a portion of which has been shown at S, silo walls being of greatly varying thickness, varying from two inches, 5 when the wall is constructed of wood, to eight inches or more when the wall is constructed of brick, concrete or the like, thus making it necessary that the hook carrying shanks have a considerable range 10 of adjustment in order that the device may be used in connection with silos of many different constructions. It is, of course, to be understood that the hook-carrying shanks may be engaged not only 15 with the top edge of the silo wall, but also with the sill of any opening or doorway in the silo.

From the foregoing description, taken in connection with the drawings hereto annexed, the operation and advantages of this 20 invention will be readily understood by those skilled in the art to which it appertains. The operator standing on the step or platform 20 may conveniently manipulate the 25 hoisting element 26 whereby a blower pipe, indicated at B, may be hoisted into position. When the blower pipe has attained the desired elevation, it is turned so as to present the spout thereof C in the desired direction, 30 after which the blower pipe is made to abut on the hooked extremities of the arms 27 where it is made fast by means of the chain 30, some of the links of said chain being placed in engagement with the hooks 29, 35 thereby sustaining the blower pipe securely in position for operation. After the silo has been filled, the pipe may be lowered and the crane detached and stored away for future use.

40 Having thus described the invention, what is claimed as new, is:—

1. In a device of the class described, a 45 frame comprising side members having forwardly extending arms at their lower ends, a step supported on said members, supporting means at the upper ends of the side members whereby the frame may be suspended in position for operation, forwardly con-

verging arms supported by the side members, and hoisting means carried by said 50 arms.

2. In a device of the class described, a frame comprising members having forwardly extending arms at their lower ends, 55 said arms having terminal hooks, inclined braces connecting the hooks with the side members, a step secured on the arms with its forward edge beneath the hooks, said step serving to connect and to space apart the lower ends of the side members, forwardly convergent arms connected with the side members, means whereby said arms are secured together at their front ends, a hoisting pulley supported by said arms, and means secured at the upper ends of the 60 side members whereby the frame may be suspended in position for operation.

3. In a device of the class described, a frame comprising side members having forwardly extending arms, a step secured on 70 said arms, forwardly convergent arms connected with the side members, a pulley supported by said arms, brace arms connecting the first mentioned arms with the side members, said brace arms being provided with 75 terminal hooks at their free ends, a chain connected with one of the arms, keepers at the upper extremities of the side members, shanks secured slidably and adjustably in the keepers, and hook members at the rear- 80 ward ends of the shanks.

4. In a device of the class described, a frame comprising suitably spaced and connected side members, a step at the lower ends of the side members, and hoisting mechanism 85 supported by the frame, brace arms reinforcing the brace mechanism and having terminal hooks and a chain connected with one of said brace arms, and means at the upper ends of the side members of the 90 frame, whereby said frame may be suspended in position for operation.

In testimony whereof I affix my signature.

WALTER EDWARD BEREITER.
